UNITED STATES PATENT OFFICE

134,186

DESIGN FOR A LAPEL BUTTON

Frank P. Coleman, Hammond, Ind.

Application July 30, 1942, Serial No. 107,768

Term of patent 3½ years

To all whom it may concern:

Be it known that I, Frank P. Coleman, a citizen of the United States, residing at 20 Elizabeth Street, Hammond, in the county of Lake and State of Indiana, have invented a new, original, and ornamental Design for Lapel Buttons, of which the following is a specification, reference being had to the accompanying drawing, forming part thereof.

I claim:

The ornamental design for a lapel button, as shown.

FRANK P. COLEMAN.
